US00D820291S

(12) **United States Design Patent** (10) **Patent No.:** **US D820,291 S**
(45) **Date of Patent:** **** Jun. 12, 2018**

(54) **DISPLAY SCREEN HAVING A GRAPHICAL USER INTERFACE**

(71) Applicant: **Amazon Technologies, Inc.**, Seattle, WA (US)

(72) Inventors: **Ryan Scott Russell**, Bellevue, WA (US); **Michael Keith Lemmon**, Seattle, WA (US); **Fransisca Vina Zerlina**, Seattle, WA (US); **Wesley Scott Lauka**, Seattle, WA (US)

(73) Assignee: **Amazon Technologies, Inc.**, Seattle, WA (US)

(**) Term: **15 Years**

(21) Appl. No.: **29/575,959**

(22) Filed: **Aug. 30, 2016**

Related U.S. Application Data

(63) Continuation of application No. 29/483,395, filed on Feb. 27, 2014, now Pat. No. Des. 768,665.

CLAIM

The ornamental design for a display screen having a graphical user interface, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a front view of a first embodiment of a display screen having a graphical user interface.

FIG. 2 is a front view of a second embodiment of a display screen having a graphical user interface; and,

FIG. 3 is a front view of a third embodiment of a display screen having a graphical user interface.

The broken line of the display screen and the other broken lines in the drawings are for illustrative purposes only and form no part of the claimed design.

1 Claim, 3 Drawing Sheets
